SOLE FLAP SPLITTING MACHINE

Robert F. Lane, Beverly, Mass., assignor to United
Shoe Machinery Corporation, Flemington, N. J.,
a corporation of New Jersey

Application March 4, 1952, Serial No. 274,711

12 Claims. (Cl. 12—16.5)

1

This invention relates to sole flap splitting machines and is herein illustrated as embodied in a machine of the type shown in Letters Patent of the United States No. 2,603,802, granted July 22, 1952, upon my application for improvements in Sole Flap Splitting Machines.

Such machines are employed, for example, in splitting a heel-breast-covering flap from the heel end of a sole and it is sometimes desired to employ them for soles which have been reduced and sometimes for those which are of uniform thickness transversely of the sole. As in the patented machine it is sometimes desired to cut a breast flap of substantially uniform thickness and sometimes to provide such a flap with a reinforcing thickened portion through the center thereof. It is also desired to so split the flap as to provide a relatively thick hinge portion where the flap is attached to the body of the sole.

One object of the invention is, therefore, to provide an improved machine capable of handling a wide variety of work with a minimum number of adjustments or changes between operations upon one type of work and another.

For the reason that an operator standing at the front of the machine desires to handle work stacked upon one side of the machine and deposit it upon the other side of the machine, he customarily takes a sole from a stack at one side and moves it transversely of the machine until it is opposite the operating point. Furthermore, at the end of the operation he usually moves the sole laterally from the operating point to the other side of the machine where it may be deposited in a receptacle or behind in a stack. Accordingly, the machine, in accordance with a feature of the invention, is now constructed with its work handling devices, such as the matrix and the work feeding roll, located close to the front of the reciprocating knife carrier of the machine and with such auxiliary parts, as the side members upon which the work supporting roll is carried, terminating substantially in a plane transversely of the machine adjacent to the work handling members. This enables the path of movement of the work as it is presented to the machine to extend transversely thereof, without requiring much front-to-back movement in presenting the work to the knife.

Associated with this feature of the invention are other features such as the location of the pressure springs at a point substantially removed from the front ends of the roll carrying arms. Still another feature of the improved arrangement of the machine permits a cam, which con-

2

trols the dipping of the work supporting roll at the completion of the forward movement of the knife carrier, to be located at the rear of the knife and between it and the crank-operated end of a connecting rod which serves to slide the carrier back and forth.

Although the machine is so constituted that it is possible to feed either a reduced sole to the work gripping members or to present a block 10 sole of full thickness, the improved machine includes manual means for adjusting an abutment for one end of the toggle which is effective to lower the work supporting roll at the termination of the splitting action. Thus, by a simple hand 15 wheel and screw mechanism the position of this abutment may be very quickly changed so that the upper end of the range of movement of the supporting roll is more widely spaced from the matrix when soles of full thickness are to be 20 presented to the machine.

Another object of the invention is to provide for accurately positioning the soles so that the hinge of the breast covering flap shall be at a predetermined distance from the heel end of the 25 sole.

This object is accomplished in the illustrated machine by providing a disappearing gage mechanism having gage members which project upwardly through the work table at the end of 30 the cycle so that they constitute, in effect, abutments against which the sole may be pressed. Such gages are, however, in the path of movement of the knife edge and if left in position would push the sole away from the knife rather 35 than permit the intended action. Accordingly, a lost-motion mechanism is provided for withdrawing the gage members below the work supporting table automatically. This withdrawal is preferably completed a short time after the 40 knife-carrying head starts to move and in the illustrated machine provision is made for adjusting the time when the automatic mechanism is made effective.

Still another feature of the invention resides in 45 an arrangement whereby a canvas curtain which is interposed between the front of the machine and the moving front end of the carrier beneath a sole is held stationary and hence does not disturb the position of the latter. To this end it is carried over a roller at the front of the knife carrier and then back under itself to a forward point where it is tensioned as by the provision of a weight.

These and other features of the invention will 50 best be understood from consideration of the

following specification taken in connection with the accompanying drawings in which

Fig. 1 is an angular view of the machine;

Fig. 2 is a vertical section through the knife carriage at approximately its center and extending along a plane parallel to the sides of the carriage;

Fig. 3 is a plan view of the machine and especially the knife carriage;

Fig. 4 is a front elevation of the work handling parts of the machine;

Fig. 5 is an elevation on a larger scale of the knife carriage, viewed from the right hand side of the machine;

Fig. 6 is a vertical front-to-back section through the machine, showing the disappearing gage mechanism;

Fig. 7 is an enlarged view also in vertical section of this gage mechanism but taken in another position of the cycle of the machine;

Fig. 8 is a plan view of the gage mechanism; and

Fig. 9 is a vertical transverse section on the line IX-IX of Fig. 8.

The machine comprises a frame 10 having a skirt 11 (Fig. 6) provided with bushings 11a. The bushings and hence the frame are secured to the tops of posts 13 within a casing 15 (Fig. 1). The base of the frame has longitudinally extending ways 12 (Fig. 4) in the form of upwardly projecting dovetail ribs to provide for reciprocation of the work handling parts of the machine. A carrier 16 which is shaped to engage the outside faces of the ways 12 (Fig. 4) is slidable lengthwise of the machine from front to back and is provided with a transverse arched member 18.

This carrier serves to support a splitting knife 20 (Fig. 6), a supporting roll 22 and a drag bar 24. It is arranged to be reciprocated along the ways 12 by a connecting rod 26 pivotaly connected to the carrier by means of a vertical pin 28 extending between the arch 18 (Fig. 2) and a transverse portion 29 of the carrier 16. The rear end of the connecting rod 26 is pivoted to a crank 30 (Fig. 6) at the upper end of a vertical shaft 32. The shaft is arranged to be driven from a source of power (not shown) by means of a worm 34 upon a transverse shaft 36 engaging a worm gear 38 at the bottom of the shaft 32. Interposed between the shaft 32 and the crank 30 there is a one-revolution clutch 40 similar to that of my earlier application, now Patent No. 2,603,802, and controlled by a cable 42 extending over a cross rod 44 on the frame and thence down to a treadle (not shown). The notches of the driving half of the clutch have been provided with square sided bottom portions to prevent chattering.

The knife 20 is detachably secured to the portion 29 of the carrier 16 by screws 31 (Fig. 3) and its forward sharpened edge lies closely adjacent to the matrix 24 (Fig. 2) and to the top of the supporting roll 22. The carrier is also provided with a table 46 (Fig. 6) through which project gage pins 48 and on the front edge of which there is a transverse roller 50. Over this roller passes a canvas curtain 52 secured at its forward end by a bar 54 to a front plate 55 removably attached to the frame of the machine. The other end of the curtain slides over a cross rod 56. This latter is supported by ears 57 on the inside of the front plate. The curtain 52 hangs down at the front of the machine just inside of the casing 15 (Fig. 1) and its lower end is weighted so that it is

5 maintained taut between the front of the machine and the roller 50 as the carrier slides back and forth with no motion of any part while that part contacts a sole.

The supporting roll 22 is made up of a series of thin, toothed disks splined to and clamped upon a transverse shaft 62 which is journaled in each of a pair of tiltably mounted side arms 64. A stripper 65 (Fig. 2) prevents the heel end of a light sole from wrapping around the roll 22. The arms 64 are pivoted upon studs 66 at the rear of the carrier 16 and on their outer sides are provided with trains of gears 68 (Figs. 3 and 5). One end of each train is secured to the supporting roll shaft 62 and the other ends of the trains mesh with the teeth of racks 70 extending lengthwise of the frame 10 beside the ways 12. As may be seen in Fig. 4, these racks lie in grooves in the frame 10 and are protected by side flanges 72, 74 integral with the frame. As a result of this arrangement the supporting roll 22 is driven clockwise, when viewed as in Fig. 5, to help to keep the work against the edge of the knife 20 thereby to split a flap from the sole.

25 On the other hand, when the carrier retreats to complete its cycle the side arms 64 are depressed by mechanism to be later described and the supporting roll is driven counterclockwise (Fig. 5) so that, while there is no movement of the sole with respect to the frame of the machine, any danger of tearing the flap is avoided because this linear speed of the top of the supporting roll is equal to the linear speed of the carrier 16 upon the frame.

30 35 It is important that the supporting roll 22 shall be held firmly in engagement with the work during the forward movement of the carrier and to that end the machine is provided with heavy springs 76 (Fig. 1) surrounding rods 78 which extend vertically at each side of the carrier. The lower ends of these rods are threaded in the side arms 64 (Fig. 5) and they pass through apertures in side lugs 80 upon the carrier. The springs 76 bear upon the upper surface of these lugs 80 and they are confined by washers and nuts 82 at the upper ends of the rods 78. The arrangement of the side arms on the carrier is such that ample space is provided for the springs 76 which may be as large as is necessary for the intended purpose of holding the supporting roll 22 in firm contact with the sole.

40 45 50 55 60 65 70 75 When it is desired to depress the roll supporting arms 64, as during the retreating movement of the carrier, this is done by means of cam-operated toggles 84. The lower portion of each toggle is made up of parallel links 86 pivoted to the side arm 64 and pivoted at 88 to the mid point of a bell crank 90 the upper end of which is rounded and received in a socket 92 of an adjustable abutment 94 pivoted on the carrier at 96. The upper ends of these abutments are joined by a crossbar 98 the position of which with respect to the carrier is determined by a hand screw 100. The shank 101 of this screw passes through an upstanding portion 102 integral with the carrier bridge 18 and is provided with a nut 104 having one end curved for easy adjustment with respect to a similarly shaped recess in the crossbar 98. Similarly, a round faced washer 106 is positioned beneath the hand wheel of the adjusting screw between it and the upward extension 102. Thus, in spite of the heavy pressure involved there is no binding of this hand screw with respect to the two portions to which it is joined, 75 and it is possible for an operator, changing from

reduced soles to those with a thick end, to change the initial position of the roll 22 without changing the extent of dipping movement caused by a mechanism which will be described now.

The lower ends of the bell cranks 90 are joined by links 108 to a U-shaped lever made of arms 110 and a cross bar 111 carrying a stud 112 at the top of which is a partly spherical ball 114 resting against the similarly curved edge of a cam plate 116 which is bolted to the underface of the connecting rod 26 between the pin 28 and the crank 30 and thus in a space away from the front and not needed for other parts of the machine. The contour of this plate is shown in Fig. 3 and the cam becomes effective when the connecting rod 26 swings on the carrier around the pin 28 as the crank rotates. When the cycle starts, the connecting rod is tilted away from the longitudinal center line of the machine viewed in plan so that the cam roll 114 moves along a portion 118 which is concentric with the axis of the pin 28. On the other hand, as the connecting rod 26 is swung to pull back the carrier, the cam roll 114 will ride up upon a hump 120 of the cam plate 116 thereby rapidly straightening the toggle 84 and causing the side arms 64 (Fig. 5) to be dipped to lower the supporting roll 22. After the cam roll passes the hump 120 it rides along a concentric portion 122 of the cam plate keeping the roll 22 depressed until the beginning of another cycle.

Similarly the matrix 24 (Fig. 5) is rotatably supported at its ends in the carrier and it has an upstanding arm 124 provided with a grooved head 126 topped by a cam roll 128. Resting in a groove of the head 126 is one arm of a U-shaped spring 130 (Fig. 3) attached at its other end to a lug 132 on a curved cross member 134 forming part of the carrier frame and carrying a removable guard plate 135 (Figs. 1, 2 and 3). It will be noted (Fig. 5) that the stud 124 passes through a slot in this cross member 134 and that the cam roll 128 rests against the rear face of a depending cam 136. This cam 136 is provided with a forked support 138 having side arms 140 which engage grooves 142 in the opposite faces of a connecting rod 26 which is a forward extension of the member 144. The extension is attached to the connecting rod 26 by a screw 145 in a slot to permit slight lateral adjustment of the member thereby to control the timing of the cam 136, thus enabling the forming of a thicker hinge if desired. A cross screw 146 joining the side arms 140 extends through a slot 148 in the extension 144 and clamps the support 138 thereto. The front and back position of the cam plate 136 with respect to the connecting rod extension 144 may be adjusted by a thumb screw 150 threaded into the end of the extension 144 and having a head which rests against the front face of the cam plate support 138. This cam plate 136 is designed to operate upon the same general principle as the cam plate 116 and is operative to tilt the matrix 24 to relieve the drag upon the upper surface of the sole during the retreating movement of the carrier.

In this matrix, as in my earlier machine, there is an oblique rod 152 (Fig. 4) which supports a matrix modifying plate 154 used to fill a recess 156, which extends across the bottom of the matrix from front to back, during a portion of the cycle of the carrier so as thereby to control formation of a strengthening rib upon the flap which is being split from the sole.

This oblique rod 152 has a threaded extension 75

158 permitting ready adjustment of its length and has a head grooved to provide spaced flanges 160 between which there is received the forked lower end 162 of a control member 164. Thus 5 adjustment of the extension does not disturb the interengagement between the forked end 162 and the grooved head. This control member 164 is attached to the forward end of a swinging lever 166 (Fig. 3) pivoted upon a stud 168 threaded in 10 a lateral extension 170 of the carrier. The control member has an integral casing 172 to receive one end of a spring 174 the other end of which bears against a side face of the bridge 18 upon the carrier 16. In the casing 172 there is an 15 adjustable bottom plate 176 to control the tension of the spring 174.

The swinging lever 166 has a depending portion 178 in which there is vertically slidably a rod 180 carrying at its lower end a riding roll 182 and a 20 somewhat larger cam roll 184. The rod 180 is grooved to receive a spring-operated retaining member 186 so that the rod may be positioned to bring the cam roll 184 against the side face of a cam strip 188. The cam strip 188 has slot 25 and screw clamping means 189 by which it is adjustably mounted upon the top of the side flange 72. One end of this cam strip is beveled to shift the matrix filling plate 154 from a position where the roll is off the cam and a strengthening rib of full height is being formed upon the flap, to a position where the cam roll 182 engages the side of the strip 188 and no rib is being formed. Adjustment of the position of this cam strip 188 enables control of the location 30 of the tapering end of the reinforcement as in my earlier machine. When, on the forward stroke of the carrier, the cam roll 184 rides off the tapered end of the cam strip, then the riding roll 182 engages the side of the flange 72 and 35 prevents further rotation of the lever 166 by the spring 174.

The disappearing gage pins 48 which extend up through openings in the table 46 and which are used to determine the location of the end 45 of a sole, are mounted upon a U-shaped pivoted support 200 (Figs. 6 and 7). The table is attached to the ends of the roll-carrying arms 64 (Fig. 5) by screws 201 (Figs. 8 and 9). This support 200 is carried by a cross pin 202 extending between upturned ends 204 upon a block 206 which slidably engages the inner and top faces of the dovetailed shaped ways 12 and which is provided with a friction gib 208 so that it will not slide upon the ways unless it is pushed. The U-shaped support 200 is held upward in the position shown in Fig. 6 by a spring 210 underlying a cross bar 212 thereon (Fig. 8).

Movement of this block 206 to the left in Fig. 6 is effected by pins 214 (Fig. 8) extending inwardly from the carrier 16 and positioned to engage upright flanges 216 near one end of the block. Movement of the block in the other direction is effected by depending lugs 220 which, as shown in Fig. 9, are T-shaped in section and 65 are adjustably mounted in grooves in the underface of a cross plate 222 secured at its ends by screws 224 and dowel pins to the bottom of the plate forming the table 46.

In order to adjust the position of the lugs 220 thereby to control the timing of the depression of the gage pin support 200, as will later appear, the mechanism includes an intermediate cross plate 226 having diagonal slots 228 (Fig. 8) for engagement with pins 230 which extend upwardly from the lugs 220 and which pass through

front-to-back slots 232 in the lower plate 222. The intermediate plate 226 is guided for movement transversely of the table by depending rectangular projections 234 which are received in slots 236 in the lower plate 222. At one end the intermediate plate 226 has an upward extension 238 to which there is attached a hand screw 240 the shank of which passes through a transverse slot 242 in the table. This screw serves as a handle to slide the plate 226 and is provided with an enlarged head resting against the upper surface of the table to clamp the intermediate plate 226 in its adjusted position. When the screw 240 is at its extreme left-hand position, as viewed in Figs. 8 and 9, a movement of the carrier 16 forward for about a quarter of an inch will cause the gage pins to disappear. Any adjustment of the screw to the right will necessitate a longer movement of the carrier before the gage pins 48 are drawn down.

Depression of the gage pin support 200, in order to prevent the pins 48 from pushing aside a sole when splitting starts, is effected by a cam nose 244 (Figs. 6 and 7) which is integral with and hangs down below the bottom plate 222. This has an inclined forward surface adapted for engagement with an inclined rearward surface 243 formed upon the cross portion of the U-shaped support 200 for the gage pins. These surfaces cooperate, as indicated in Fig. 7, to depress the gage pin support 200 soon after the carrier 16 starts to move forward toward the operator to grip the end of the sole between the matrix roll 24 and the supporting roll 22. At this point the side pins 214 on the carrier 16 will engage the upright flanges 216 at the rear end of the plate 206. From there on, for the rest of the forward movement of the carrier 16, the gage support 200 will remain in the position shown in Fig. 7. However, when the carrier starts upon its retrograde movement, away from the operator, the pins 214 will be moved away from the vertical flanges 216 and, owing to the friction between the block 206 and the ways 12, the block and its gage pin support will remain motionless until the depending lugs 220 come against the end of the block 206 and start to move it rearwardly. Just before this the nose 244 will have slipped over the cam surface 243 on the pin carrier allowing the pins to rise into engagement with the undersurface of the sole. This, however, will do no harm because the cutting operation will have been completed at that time.

In the use of the machine the action of the parts will take place in the same sequence as was described in connection with the earlier machine save as regards this gage mechanism, the operation of which has been just described. Briefly, a sole will be placed upon the table 46 and will also be supported partially by the canvas holding bar 54. As the operator depresses the treadle, setting in motion the crank 30 and its connecting rod 26, the carrier 16 will be reciprocated and the knife moved forward to split a flap from the sole. During this movement the supporting roll 22 will be rotated clockwise, as seen in Fig. 6, being driven by the interaction of the gears on the carrier with the racks 70 along the sides of the frame and the shape of the flap will be determined by the matrix 24 and its recess 156 together with the shiftable matrix plate 154. The shifting movement of this plate 154 will be effected by the cam 186 acting upon the roll 184. At the start of the return movement of the carrier the matrix 24 will be tilted to release the flap and the roll

22 will be turned in the opposite direction, being also depressed by the action of the cam 116.

Having thus described my invention what I claim as new and desire to secure by Letters Patent of the United States is:

1. In a splitting machine, a base, a carrier slideable on the base, a splitting tool on the carrier, a drag bar above the tool, means tiltable on said carrier for supporting the work against the drag bar, a crank for providing power to move the carrier, a connecting rod joined to said crank and pivoted on the carrier, means for depressing the supporting means to carry it to inoperative position, springs adjacent to the free end of the tiltable support for holding it in operative position, and a cam on the connecting rod between the point of its attachment to the carrier and the crank for operating said depressing means.

2. In a splitting machine, a base, a carrier slideable on the base, a splitting tool on the carrier, a roll support tiltable on the carrier, a roll for supporting the work journaled in said support, spring means for holding said roll support in operative position, a crank for providing power to move the carrier, a connecting rod joined to said crank and pivoted on the carrier, a toggle for depressing the support to carry the roll to inoperative position, springs for holding the roll in operative position, a cam for operating said toggle, an abutment on the carrier for one end of the toggle and manually adjustable means for varying the position of said abutment.

3. In a splitting machine, a carrier, a knife and a work supporting means movable with said carrier lengthwise of the machine, a matrix presser member on said carrier having a recess, a movably mounted modifying device for rendering the matrix recess ineffective, a movably mounted arm for operating said matrix modifying device, a grooved head adjustably attached to said device, means on said arm engaging the groove of said head, and means for moving said arm as the carrier is moved along the work.

4. In a splitting machine, a knife, means for producing relative movement between a piece of work and said knife, means for controlling the work as said relative movement takes place comprising a drag bar and an opposed supporting member, said drag bar having a matrix recess, a device associated with said drag bar and movable so as progressively to fill the recess, a grooved head threaded to said device, and an arm operated by said relative movement producing means engaging said groove to effect movement of said matrix filling device in timed relation to said relative movement.

5. In a splitting machine, a knife, a movable carrier therefor having a transverse rod, means for reciprocating said knife carrier to split the heel end of a sole, a work table adjacent to the front of the knife carrier underlying the work in various positions of said carrier, a fixed plate at the front of said carrier, a flexible sheet fastened to said fixed plate and extending over said rod, and means for keeping said sheet taut as the cutting action progresses without moving that portion of the sheet which underlies the forward part of the sole.

6. In a splitting machine, a base, a knife carrier slideable on the base, a work table secured to said carrier, a slide guided for front and back movement and having a lost-motion connection to said carrier, a gage normally projecting above said work table movably mounted on said slide for up-and-down movement with respect thereto,

and interacting means between the table and the slide for withdrawing the gage beneath the table upon relative movement between the table and the slide.

7. In a splitting machine, a base, ways extending along the base, a knife carrier slidably engaging the outer sides of said ways, said carrier having an apertured work table, gage pins projecting through said apertures to terminate above the table, a slide frictionally engaging the inner sides of the ways, means on the carrier to push said slide back and forth with lost motion between the two, a support for said gage pins tilttable on the slide, and coacting surfaces upon the table and the tilttable support operative to withdraw the gage pins beneath the table as a result of the relative movement between the table and the slide.

8. In a splitting machine, a base, a carrier having a work table, said carrier being slidable on the base, a slide having a delayed movement with respect to the carrier, yieldable means on the slide, gage pins carried by said means and projecting above the table, and a cam upon the table for depressing said yieldable support upon relative movement between the carrier and the slide.

9. In a splitting machine, a base, a carrier slidable upon the base, a gage carrying slide slidable adjacent to the carrier, said carrier having abutments providing a lost-motion connection between the carrier and the slide, and means operative upon relative movement between the carrier and the slide for depressing the gage.

10. In a splitting machine, a base, a carrier slidable upon the base, a gage carrying slide slid- able on the base adjacent to the carrier, said car- 35

rier having abutments providing a lost-motion connection between the carrier and the slide, and means operative upon relative movement between the carrier and the slide for depressing the gage, the abutment engaging one end of the slide being movably supported upon the table.

11. In a splitting machine, a base, a carrier slidable upon the base, a gage-carrying slide slidable on the base adjacent to the carrier, said carrier having abutments providing a lost-motion connection between the carrier and the slide, means operative upon relative movement between the carrier and the slide for depressing the gage, the abutment upon the table end of the carrier being slidable thereon from front to back, and a transversely adjustable slide connected to said abutments to control their position upon the table.

12. In a splitting machine, a base, a carrier slidable upon the base, a slide having a lost-motion connection to said carrier, a U-shaped lever pivoted at the rear of the slide and having an inclined cam surface on its transverse portion, gage pins on said U-shaped support, said carrier having a depending cam adapted to contact said cam surface upon relative movement between the slide and the carrier to withdraw the gage pins beneath the surface of the table.
